X-RAY TUBE

Adrianus Verhoeft, Eindhoven, Netherlands, assignor to N. V. Philips' Gloeilampenfabrieken, Eindhoven, Netherlands

Application July 17, 1936, Serial No. 91,237
In Germany August 12, 1935

10 Claims. (Cl. 250—142)

My invention relates to X-ray tubes and more particularly to X-ray tubes for treating cavities or for contact therapy.

X-ray tubes used for the above purposes must be comparatively small, and it is exceedingly difficult to connect same to a supply source in a manner which is safe and at the same time does not interfere with the use of the tube. In prior constructions this has been effected by using a terminal piece secured to a supply cable and provided with means for electrically and mechanically interconnecting the tube and cable. Such constructions, however, have the drawback that the terminal piece increases the diameter of the assembly, and greatly impedes the introduction of the tube into the cavities to be irradiated. In addition with the X-ray tube used for this purpose, a large amount of the heat developed in the anode is transmitted toward the cable end of the tube, and deleteriously affects the insulating material of the cable.

One object of my invention is to provide an X-ray device comprising an X-ray tube and a supply cable which are mechanically and electrically connected without the use of additional insulating terminal pieces.

A further object of my invention is to provide an X-ray device in which the outer surface of the X-ray tube forms a continuation of the surface of the supply cable.

A still further object is to reduce the amount of heat transmitted toward the cable end of the tube.

In accordance with the invention, I provide a high-tension supply cable at one end with a cavity into which one end of an X-ray tube snugly fits, and mechanically and electrically connect the tube and cable without the use of additional insulating terminal members.

In order to permit the X-ray tube and cable to be readily handled for irradiating cavities, I make the diameter of the projecting portion of the tube substantially the same as that of the cable, whereby the tube and cable form a substantially cylindrical body.

To prevent the body to be irradiated from coming into contact with members of the assembly under high-tension I form the projecting portion of the tube envelope as a metal cylinder, and connect same to ground.

Furthermore, to assure rigidity of the assembly and also to prevent rupture of the glass envelope portion by excessive bending, I surround the metal cylinder and the adjacent portion of the cable with a metal tube. This metal tube also

serves to ground the metal cylinder by connecting same to a grounded layer provided on the cable.

For electrically connecting the conductor of the cable to the high-tension electrode of the X-ray tube, as well as for mechanically securing the tube to the cable, I provide on the end of the glass portion extending into the cable a metal supporting member carrying the high-tension electrode, and cooperating with a contact member permanently secured to the conductor of the cable. This metal member may also serve for exhausting the X-ray tube and may be closed after exhaustion with a glass press which is protected by the cable.

To reduce the amount of heat transmitted towards the cable end of the tube, I support the anode from the envelope by means of a supporting member of low heat conductivity, or the metal supporting member may be interrupted by a thermal insulator, such as a glass tube which of course must be shunted, for instance by a conductive coating, in order to allow passage of current to the anode.

In order that my invention may be clearly understood and readily carried into effect, I shall describe same more fully with reference to the accompanying drawing, in which:

Figure 1 is a sectional view of an X-ray tube device according to the invention, and

Fig. 2 is a sectional view of an X-ray tube according to the invention.

The X-ray tube shown in Fig. 1 has an evacuated envelope comprising a cylindrical metal portion 1 and a tapering or funnel-shaped glass portion 2 sealed together at 3. Closing the upper end of cylinder 1 and sealed thereto at 4 is a glass window 5 for the exit of the X-rays. Sealed at 30 to the lower end of the glass portion 2 and extending downwardly into a tapering portion 21, and also extending upwardly, is a metal tube 6 to the upper end of which is sealed a glass tube 9. To the upper end of tube 9 is sealed a metal tube 8 provided with an aperture 24. The lower end of the tube 6 is provided with a glass tip 23 whereby the X-ray tube is exhausted through aperture 24 and the tubes 6, 8 and 9.

The X-ray tube is provided with a cylindrical-shaped anode 7, which may be of tungsten, supported from the metal tube 8 by a metal member 12 having an enlarged lower end 11, which closes the end of tube 8. The member 12 and the glass tube 9 serve to reduce the amount of heat transmitted from the anode 7 to the end of the tube. The member 12 is provided with a disc 13, for instance of tungsten, which serves to prevent un-

desirable rearward radiation of heat and thereby protects the seal 3 from being overheated by radiation from the anode. It also absorbs X-rays emanating in rearward direction.

5 To electrically connect tubes 6 and 8, and thus to connect the anode to the tube 6, a thin metal coating 10 is provided over the surface of the glass tube 9 and is connected to the tubes 6 and 8. The coating 10 may also serve as a protective 10 resistance.

10 Above the anode 7 is a V-shaped cathode filament 14 supported at its apex by a central support 15 and at its ends by two lead-supports 31; only one of the supports 31 being visible in Fig. 1.

15 The support 15 is insulatingly secured to the metal tube 1 whereas the supports 31 pass in a vacuum-tight manner through glass beads 40 sealed in the tube 1. One of the lead-supports 31 may be electrically connected to the metal cylinder 1, in which case the tube is operated 15

20 with a grounded cathode. However, there may also be a small potential difference in which case both of the leads 31 are insulated from the cylinder 1 and are connected to low-tension conductors for the supply of the cathode heating 25 current.

25 High-tension current is supplied to the X-ray tube through a high-tension cable having a hollow flexible conductor 16, for example of wire netting, within which is a core 26 of insulating 30 material, for instance rubber. Surrounding the conductor 16 is an insulating body 17, for instance of rubber, whose end is provided with a cavity snugly fitting the funnel-shaped glass portion 2.

35 An outer metal tube 18 surrounds the X-ray tube and a portion of the cable and thereby provides sufficient rigidity to prevent damaging of the glass portion of the tube envelope. Secured 40 to the upper end of metal tube 18 is a protecting hood 28 of an X-ray transparent material, such as aluminium or metallized Celluloid, which protects the glass window 5. The inner diameter of tube 18 is preferably made slightly larger 45 than the diameter of the cable so that it fits over the cable with a small amount of clearance. There is also a small space between the tubes 1 and 18 so that the wires 32 connected to the leads 31 may be insulatingly enclosed in this 50 space and brought out at 35.

55 Secured to the lower end of tube 18 is a metal connecting piece 19 electrically connecting tube 18 to a grounded layer 20 of wire netting covering the cable.

60 The tube 18 is centered in the cylinder 1 by means of a plurality of elastic members, for example three in number, one of which is shown at 33, these members being secured to tube 18 at 34.

65 The electrical connection between the anode 7 and the conductor 16 is effected by means of a metal cylindrical member 25 detachably secured, for example by screw threads, to the portion 21 and permanently secured to the cable at the bottom of the cavity. To secure the member 25 to the cable so that it will not become detached when removing the X-ray tube, the core 26 is bored and is expanded, for instance by a central wedge shown as a wood screw 27, against the inner wall of the metal tube 16. In this manner 70

75 the lower end of member 25 is brought into good electrical contact with the upper end of conductor 16 and is also securely fixed so that it will not become loosened upon removal of the X-ray tube.

76 It will be noted that the assembly of the X-ray

tube and cable has no radially-projecting parts and that the high-tension parts are not in contact with the open air. Due to this, the tube may be readily introduced into cavities of the body without the danger of electrical shocks; the device thus being particularly adapted for short-distance treatment. Furthermore, it should be noted that the enclosed air space lying between the exhaust connection 23 and the screw 27 will cause no disturbing effect, as it is surrounded by the metal portion 25 which is under tension and therefore an electric field cannot occur in this space. In order to avoid air pockets between the glass wall 2 and the rubber body 17, I apply a little insulating fluid, such as ricinus oil to the outer surface of the glass portion 2 before putting it into the cable.

80 To facilitate handling of the device, a handle 29 is secured to connecting part 19 or it may be secured to the metal tube 18.

85 Fig. 2 shows a portion of an X-ray tube which is similar to that shown in Fig. 1 with the exception that the glass member 9 and metal member 6 are omitted and the bottom portion of the envelope is formed as a usual reentrant portion 42. To the re-entrant portion 42 is sealed a metal cylinder 48 whose upper end is closed by the projecting portion 11 of the support 12. In this construction the tube is exhausted at 43. A metal tube 44 serves for the electrical connection 30 of tube 48 with the conductor 16 of the cable. It is provided with a slit 45 for the passage of the exhaust stump 43. The upper end of tube 44 has a slightly enlarged diameter and is formed as a spring contact by means of slits 46, so that it 35 bears on the inner wall of tube 48.

90 As stated above, the member 12 serves to reduce the amount of heat transferred to the lower portion of the tube and for this purpose is made of an electrically-conductive material of low heat 40 conductivity, for instance chrome-iron, and/or is given a small cross-sectional area and made hollow.

95 Similar to Fig. 1, a disc 13 of X-ray absorbing material, such as tungsten, serves to prevent undesired radiation of X-rays. The space 47 between the glass portion 42 and the rubber body 17 and between the reentrant glass portion and the tube 44 is filled up with an insulating substance, such as the material known under the 50 name De Kothinsky cement.

100 While I have described my invention in connection with specific examples and applications, I do not wish to be limited thereto, but desire the appended claims to be construed as broadly as 55 permissible in view of the prior art.

What I claim is:—

1. An X-ray device comprising an X-ray tube having an envelope and electrodes, a flexible high-tension supply cable having a conductor, 60 and resilient high-tension insulation provided at one end with a cavity, a portion of said envelope snugly fitting into said cavity and being embraced by said insulation without radial intermediate spaces, the portion of the insulation receiving the 65 envelope having substantially the same outside diameter as the insulation covering the conductor, and means within said cavity for electrically and mechanically connecting said tube and cable.

2. An X-ray device comprising an X-ray tube 70 having an envelope and electrodes, a high-tension supply cable having a conductor and high-tension insulation, said insulation being provided at one end with a cavity, a portion of said envelope snugly fitting into said cavity without 75

- radial intermediate spaces, the portion of the tube envelope extending from the cable being substantially cylindrical and of substantially the same outside diameter as the insulation of the 5 cable, and means within the cavity for electrically and mechanically interconnecting said tube and cable.
3. An X-ray device comprising an X-ray tube having an envelope and electrodes, said envelope having a cylindrical metal portion and a portion of insulating material, a high-tension cable having a conductor and high-tension insulation, said insulation being provided at one end with a cavity, said insulating portion snugly fitting into said 10 cavity without radial intermediate spaces, means within said cavity for electrically and mechanically interconnecting said tube and cable, and a metal member closely surrounding said metal portion and the adjacent portion of the cable.
- 20 4. An X-ray device comprising an X-ray tube having an envelope and electrodes, said envelope having a tapering portion of insulating material, and a cylindrical metal portion surrounding one of said electrodes, a metal member secured to said insulating portion and supporting the electrode surrounded by said metal portion, a high-tension cable having a conductor and high-tension insulation and provided at one end with a cavity, said tapering portion snugly fitting into 25 said cavity, and means including said metal member electrically and mechanically interconnecting said tube and cable.
- 30 5. An X-ray device comprising an X-ray tube having an envelope and electrodes, said envelope having a funnel-shaped portion of insulating material and a cylindrical metal portion surrounding one of said electrodes, a metal tube secured to said funnel-shaped portion and supporting the electrode surrounded by said metal portion, a high-tension cable having a conductor and high-tension insulation and provided at one end with a cavity, said funnel-shaped portion snugly fitting said cavity, means including said metal tube for electrically and mechanically interconnecting said X-ray tube and cable, and a vitreous 35 pump-connecting member closing the end of the metal tube.
- 40 6. An X-ray device comprising an X-ray tube having an envelope and electrodes, said envelope having a tapering portion of insulating material and a cylindrical metal portion surrounding one of said electrodes, a metal tube secured to said tapering portion and supporting the electrode surrounded by said metal portion, a high-tension cable having a conductor and high-tension insulation and provided at one end with a cavity, said tapering portion snugly fitting into said cavity, and means including said metal tube electrically connecting said conductor to the electrode 45 surrounded by said metal portion, said means comprising a metal connecting member mounted at the bottom of the cavity and permanently secured to the conductor of the cable.
- 50 7. An X-ray device comprising an X-ray tube having an envelope and electrodes, said envelope having a tapering portion of insulating material and a cylindrical metal portion surrounding one of said electrodes, a metal tube secured to said tapering portion and supporting the electrode surrounded by said metal portion, a high-tension cable having a conductor and high-tension insulation and provided at one end with a cavity, said tapering portion snugly fitting into said cavity, and means including said metal tube electrically connecting said conductor to the electrode 55 surrounded by said metal portion, said means comprising a metal connecting member extending between said core and conductor, and means to expand the core against said member to secure same to the cable and to electrically connect same to the conductor in a permanent manner.
- 60 8. An X-ray device comprising an X-ray tube having an envelope, an anode and a cathode, said envelope having a tapering vitreous portion and a metal cylinder surrounding said anode, means to support said anode comprising a metal tube sealed to said vitreous portion and a connecting member of low thermal conductivity, a high-tension cable having a conductor and high-tension insulation and provided at one end with a cavity, said vitreous portion snugly fitting into said cavity, and means including said metal tube and connecting member for electrically connecting the anode to the conductor and comprising a metal 65 member permanently secured to said conductor and detachably secured to said metal tube.
9. An X-ray device comprising an X-ray tube having an envelope, an anode and a cathode, said envelope having a tapering vitreous portion and a metal cylinder surrounding said anode, means to support said anode comprising a metal tube sealed to said vitreous portion and a glass tube interrupting said metal tube and sealed thereto, an electric shunt across said glass tube, a high-tension cable having a conductor and high-tension insulation and provided at one end with a cavity, said vitreous portion snugly fitting into said cavity, and means including said metal tube and connecting member for electrically connecting the anode to the conductor and comprising a metal member permanently secured to said conductor and detachably secured to said metal tube.
10. An X-ray device comprising an X-ray tube having an envelope, an anode and a cathode, said envelope having a tapering vitreous portion and a metal cylinder surrounding said anode, means to support said anode comprising a metal tube sealed to said vitreous portion, and a glass tube interrupting said metal tube and sealed thereto, and a resistance in series with the anode and supported by said glass tube, a high-tension cable having a conductor and high-tension insulation and provided at one end with a cavity, said vitreous portion snugly fitting into said cavity, and means including said metal tube and connecting member for electrically connecting the anode to the conductor and comprising a metal member permanently secured to said conductor and detachably secured to said metal tube.

ADRIANUS VERHOEFF.
